United States Patent Office.

ARCHIBALD McCALLUM, OF HALIFAX, ENGLAND, ASSIGNOR TO W. & I. SLOANE, OF NEW YORK CITY.

Design No. 4,738, dated March 28, 1871.

DESIGN FOR A CARPET-PATTERN.

The Schedule referred to in these Letters Patent and making part of the same.

all whom it may concern:

Be it known that I, ARCHIBALD McCALLUM, of Halifax, in the county of York, England, have invented a new and original Design for a Carpet, of which the following is a specification.

The nature of my design is fully represented in the accompanying photographic illustration, to which reference is made.

I claim as my invention—

The design for a carpet, as shown.

ARCHIBALD McCALLUM. [L. S.]
